UNITED STATES PATENT OFFICE.

ELMER E. GUSTAFSON, OF SULLIVAN, MICHIGAN.

COLLAPSIBLE FUNNEL.

1,373,722.

Specification of Letters Patent.

Patented Apr. 5, 1921.

Application filed May 14, 1920. Serial No. 381,387.

To all whom it may concern:

Be it known that I, ELMER E. GUSTAFSON, a citizen of the United States, residing at Sullivan, in the county of Muskegon and State of Michigan, have invented certain new and useful Improvements in Collapsible Funnels; and I do hereby declare the following to be a full, clear, and exact description of the invention, such as will enable others skilled in the art to which it app pertains to make and use the same.

This invention relates to new and useful improvements in funnels and has for its primary object the provision of a collapsible device adapted to be positioned within the filling spout or neck of a radiator when not in use and which may be readily lifted outwardly of the spout or neck and spread so that fluid may be easily poured into the radiator and also the device may be used in connection with other parts of an automobile for directing fluid into restricted or small openings.

Another object of this invention is the provision of a plurality of pivotally connected members to form the walls of the device which members may be easily and quickly folded or extended in relation to each other so as to provide an extremely compact device when folded and to provide a device of considerable size when extended so that a comparatively large volume of fluid may be poured.

A further object of this invention is the provision of means for preventing the members from separating from each other when extended.

A still further object of this invention is the provision of a collapsible funnel of the above stated character, which shall be simple, durable, and efficient, and which may be manufactured and sold at a comparatively low cost.

With these and other objects in view as will become more apparent as the description proceeds, the invention consists in certain novel features of construction, combination, and arrangement of parts as will be hereinafter more fully described and claimed.

For a complete understanding of my invention reference is to be had to the following description and accompanying drawings, in which:—

Figure 1 is a sectional view illustrating the filling spout of an automobile radiator

with a funnel therein and constructed in accordance with my invention.

Fig. 2 is a similar view illustrating the funnel positioned for use.

Fig. 3 is a perspective view illustrating the funnel.

Fig. 4 is a detail perspective view, illustrating one of the members of one of the end walls in full lines and the other members in dotted lines.

Fig. 5 is a similar view illustrating one of the side walls.

Fig. 6 is a longitudinal sectional view taken on the line 6—6 of Fig. 1.

Fig. 7 is a fragmentary perspective view, illustrating the lugs for limiting the movement of the plates constituting the sides of the funnel.

Fig. 8 is a fragmentary bottom plan view illustrating the same.

Referring in detail to the drawing, the numeral 1 indicates a funnel including side and end walls and said side walls are constructed from plates 2, 3, 4, 5 and 6 and the end walls are constructed from plates 7, 8, and 9.

The plates 7 and 9 of the end walls are formed integrally with the plates 2 and 6 of the side walls and are constructed from angle irons. The plates of the side walls are pivotally connected at one of their ends as illustrated at 10 while the plates of the end walls are pivotally connected at one of their ends as illustrated at 11, thereby

providing a construction wherein the plates of the side and end walls may be folded one over the other to form a very compact device which will fit within the filling neck or spout 13 of a radiator 14 of an automobile,

and the plates 8 of the end walls have formed upon their upper ends clips or supporting members 15 adapted to engage the annular shoulder 16 formed within the filling spout or neck of the radiator 14 for the purpose of preventing the funnel 1 from falling downwardly within said radiator.

When desiring to fill the radiator 14 with fluid, the funnel 1 is lifted until the pivots 11 and 10 are in a plane slightly above the annular shoulder 16 of the filling spout or neck 13 and the plates forming the side and end walls are extended or swung on their pivots to unfold the device and to form a funnel as shown in Figs. 2 and 3 respectively.

When the device is in the position as shown in said figures, fluid can then be easily poured into the filling neck or spout

of the radiator. The pivots 10 and 11 hold the plates of the side and end walls in frictional contact with each other so that when the device is unfolded and ready for use, a comparatively tight connection is established between said plates or members to prevent the fluid from escaping between said plates during its passage through the funnel.

10 The plates 8 of the end walls have formed on their pivoted ends inwardly and outwardly directed tongues or stops 17 and 18. The tongues or stops 17 are adapted to limit the movement of the plates 7 from the plates 8 while the tongues or stops 18 are adapted to limit the movement of the plates 9 from the plates 8 thus preventing the plates of the end walls from separating when the device is in an operative position.

15 The plates 4 and 5 have stops 19 and the stop on the plate 4 is engaged by the plate 5 while the stop on the latter engages the plate 6. The plates 4 and 3 are provided with stops 20 and the stop 20 on the plate 4 is engaged by the plate 3 and the stop 20 on the plate 3 is engaged by the plate 2, thus the stops 19 and 20 limit the movement 20 of the plates 2, 3, 4, 5, and 6 with respect to each other, and thereby prevent separation of the plates when the device is in operative position and which will permit of the plates being swung one over the other to collapse the device.

25 30 35 While I have shown and described the preferred embodiment of my invention, it will be understood that minor changes in construction, combination, and arrangement of parts may be made without departing 40 from the spirit and scope of the invention as claimed.

Having thus described my invention, what I claim is:—

1. A funnel comprising a body including 45 side and end walls, a plurality of plates constituting said walls, means pivotally connecting the plates of said walls together and means formed on some of the plates of said walls and adapted to engage the 50 other plates of said walls to limit the movement of the plates away from each other.

2. A funnel comprising a body including side and end walls, a plurality of separable

plates forming said walls, means pivotally connecting the plates of each wall together, 55 the end plates of the side and end walls being formed integrally with each other, and stops formed on some of the plates of said walls and engaging the other plates of said walls to limit the movement of said plates away from each other.

3. A collapsible funnel comprising side and end walls, each including a plurality of plates, means for pivoting the plates of each wall together so that they may be positioned to lie one over the other and swing to extend radially from their pivots, and means for limiting the movement of said plates radially.

4. A collapsible funnel comprising side 70 and end walls, each including plates, pivots connecting the plates of each wall together at their lower ends and adapted to allow the plates of each wall to be positioned one over the other and to swing in a direction 75 away from each other, means limiting the movement of said plates.

5. A collapsible funnel comprising side and end walls, each including a plurality of plates, said end walls having a smaller number of plates than the side walls, pivots connecting the lower ends of the plates of each wall and adapted to permit the plates to be positioned one over the other so as to extend parallel with each other, said 80 plates adapted to be swung radially from their pivots with their edges in overlapping relation, and stops carried by some of said plates of each wall and adapted to engage other plates when moved to extend radially from their pivots.

6. A funnel comprising a body including side and end walls consisting of plates, means pivotally connecting the plates of each wall, the end plates of each wall being 95 formed integrally with the end plates of the adjacent wall, and stops carried by some of the plates of each wall for limiting the movement of said plates with relation to each other.

In testimony whereof I affix my signature in presence of two witnesses.

ELMER E. GUSTAFSON.

Witnesses:

ARTHUR GUSTAFSON,
OSCAR GUSTAFSON.
